UNITED STATES PATENT OFFICE.

MORGAN R. BUTLER, OF WAUKESHA, WISCONSIN.

MATERIAL-HANDLING EQUIPMENT.

Application filed April 9, 1925. Serial No. 21,875.

In handling sand, gravel and other material such as used in connection with building operations, the material is discharged from a supply bin or hopper into a measuring hopper positioned therebeneath and connected therewith by a suitable valved opening or passage. The gravel, sand or the like often-times contains sticks or other foreign matter, which interfere with the closing operation of the valve or gate between the supply bin and measuring hopper when caught in the valve opening or passage between the bin and hopper.

With the above and other objections to devices of this character in mind, this invention has as one of its objects the provision of means whereby ready access may be had to the valve for controlling the passage of material from the supply bin to the measuring hopper whereby the removal of any obstruction may be readily accomplished and free access had thereto for any purpose without necessitating the complete discharge of material from the supply bin.

Another object of this invention resides in the provision of an improved hand-hole for permitting access to the valve structure formed by cutting a portion from one wall of the measuring hopper, which portion provides a closure for the opening.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a view, partly in side elevation and partly in section, of a material handling equipment embodying my invention, the upper portion of the supply hopper or bin and the lower portions of the measuring hoppers not being shown;

Figure 2 is an enlarged, fragmentary, detail view illustrating the manner of forming the hand-hole in the measuring hopper and the formation of the closure therefor, and

Figure 3 is a view similar to Figure 2 illustrating the hand-hole with its cover, a portion of the hand-hole cover being broken away.

Referring now more particularly to the accompanying drawing, the numeral 5 designates a pair of spaced, parallel, channel beams, but one being shown, forming a support for a supply hopper or bin 6 which, in the present instance, is divided by a partition 7 to form a sand compartment 8 and a gravel compartment 9. The bottom of the supply bin or hopper is formed by a plate 10 extending across the beams 5 and the plate 70 is provided with openings 11 communicating with the respective compartments, but one being shown, and with a measuring hopper, now about to be described.

The measuring hoppers 12 and 13 are supported from the beams 5 beneath the compartments 8 and 9, respectively, by suspension rods 14, the hoppers being connected with their respective compartments through passage-ways 15 extending between the beams 5, in the manner illustrated in Figure 1. The bottoms of the hoppers are provided with suitable releasable closures, not shown, and valve or gate members 16 are movable across the passage-ways 15 to control the flow of material from the supply bin to the hoppers. The gate or valve construction may be of any desired type and the one illustrated in the drawing connecting the compartment 9 with its measuring hopper 13 is of that type illustrated in my co-pending application, Serial Number 577,585, the valves being controlled from a rod 17 connected with a suitable control lever, not shown.

Sticks or other débris are often found in the material and frequently damage or obstruct the gate or valve members, thus preventing their full operation and, heretofore, it has been a difficult task to free such a jam or obstruction without disturbing the operation of the apparatus. In the accompanying drawing, I illustrate means for permitting the easy release of any obstruction without interfering, in any way, with the operation of the apparatus.

Each measuring hopper has a hand-hole opening 18 formed in one side wall thereof adjacent its upper end which is normally closed by a door 19 of the construction hereinafter described. When the gate or valve member becomes obstructed by a stick or other débris as illustrated in Figure 1, the

gate or valve member 20 is moved to closed position as far as possible after the measuring hopper has filled and the contents of the measuring hopper then discharged and the hopper bottom immediately closed again. The door 19 is then removed and the obstruction withdrawn either by the operator reaching his hand through the opening 18 or else by prying through the opening with a bar or other means. Likewise, if it is necessary to make any repairs to the gate member 16 or its associated parts, the same may be readily performed through the opening 18 as will be readily apparent. When the obstruction has been removed or the repairs completed, the door 19 is replaced and the gate member then opened if it is desired to fill the measuring hopper.

The hand-hole opening 18 is preferably formed by cutting a section of the hopper side wall therefrom by an acetylene torch or any other means 21 and the section which is removed forms the closure 19, diagonal blocks 22 being secured across the corners of the opening 18 by welding or other means. Catch members 23 are pivoted, as at 24, to opposite sides of the opening 18 and provide means for readily removably securing the closure 19 in position.

From the foregoing description taken in connection with the accompanying drawing it will be readily apparent to those skilled in the art to which an invention of this character appertains that I provide novel and improved means for permitting access to the interior of an apparatus of the character described adjacent its control gate or valve and that the hand-hole and cover therefor is formed in a very economical and effective manner.

What I claim as my invention is:

1. In a material handling apparatus having a supply bin, a measuring hopper disposed therebeneath and connected therewith by a solid wall enclosure, a valve member for controlling the flow of material from the bin to the hopper, the enclosure having a hand-hole opening in its side wall adja-

cent its point of communication with the supply bin, and said opening being closed 50 by a section of the original material cut therefrom to form the opening.

2. In a material handling apparatus having a supply bin, a measuring hopper disposed therebeneath and connectable therewith and a valve member for controlling the flow of material from the bin to the hopper, the measuring hopper having a hand-hole opening in its side wall adjacent its point of communication with the supply bin, and means normally closing said hand-hole opening whereby access may be had to the valve member to remove obstructions to its operation.

3. In a material handling apparatus having a supply bin, a measuring hopper disposed therebeneath and connectable therewith and a valve member for controlling the flow of material from the bin to the hopper, the measuring hopper having a section cut 70 from its side wall adjacent its point of connection with the supply bin to form a hand-hole through which access may be had to the valve member, and means for removably securing the section cut from the hopper in 75 forming the hand-hole in the hole to provide a closure therefor.

4. In a material handling apparatus having a supply bin, a measuring hopper disposed therebeneath and connectable therewith and a valve member for controlling the flow of material from the bin to the hopper, the measuring hopper having a section cut from its side wall adjacent its point of connection with the supply bin to form a hand-hole through which access may be had to the valve member, means extending into said opening from the inner face of the hopper wall and against which the section provided by the formation of the hand opening may 90 be secured, and releasable latch means for securing said section in a position closing said hand-hole opening.

In testimony whereof I affix my signature.

MORGAN R. BUTLER.
